AUTOMOBILE CUSPIDOR

Douglas B. Pinguely, 1314 N. Fort Thomas Ave.,
Fort Thomas, Ky. 41075

Filed Sept. 17, 1974, Ser. No. 506,798

Term of patent 14 years

Int. Cl. D7—07

U.S. Cl. D7—190

FIG. 1 is a perspective view of an automobile cuspidor showing my new design arranged for base mounting;

FIG. 2 is a top plan view;

FIG. 3 is a front elevational view;

FIG. 4 is a bottom plan view;

FIG. 5 is a side elevational view;

FIG. 6 is an exploded perspective view of the automobile cuspidor with the lid open;

FIG. 7 is a top plan view of the automobile cuspidor arranged for side mounting; and

FIG. 8 is a side elevational view of the automobile cuspidor as arranged in FIG. 7.

I claim:

The ornamental design for an automobile cuspidor, substantially as shown.
